UNITED STATES PATENT OFFICE.

GEORGE WILLIAM GRAY, OF HOUSTON, TEXAS.

METHOD FOR CONVERTING HIGHER-BOILING PETROLEUM HYDROCARBONS INTO LOWER-BOILING PETROLEUM HYDROCARBONS.

1,193,540.

Specification of Letters Patent.

Patented Aug. 8, 1916.

Application filed January 23, 1913. Serial No. 743,713.

To all whom it may concern:

Be it known that I, GEORGE WILLIAM GRAY, a citizen of the United States, residing at Houston, in the county of Harris and State 5 of Texas, have invented certain new and useful Improvements in Methods for Converting Higher-Boiling Petroleum Hydrocarbons into Lower-Boiling Petroleum Hydrocarbons, of which the following is a 10 specification.

My invention consists in novel methods for converting higher-boiling petroleum hydrocarbons of complex molecules into lower-boiling petroleum hydrocarbons of a simpler 15 molecule.

I have discovered that substantially all the higher-boiling hydrocarbons can be converted into naphtha or gasoline if they be heated, in the presence of a suitable agent, 20 to a temperature not substantially above the end-boiling-point of naphtha.

Naphtha is a general term which includes a number of different grades of gasoline. Naphtha, illuminating oils, etc., are made 25 up of individuals having different boiling points. In making a distillation test on a sample of naphtha or gasoline, for example, a quantity is introduced into a flask provided with a thermometer, the outlet of the 30 flask being connected to a condenser. Heat is gradually applied. The temperature at which the first liquid drops into the receiving flask is called the "initial boiling point". From time to time as the flow of liquid 35 ceases, the temperature is slightly raised. The temperature at which no oil is left in the flask is called the "end boiling point". Gasoline or naphtha is a product which will begin to distil anywhere from about 70° to 40 150° F., and will all distil off below a temperature of about 350° to 400° F.; while illuminating oil is a product which will begin to distil anywhere from about 310° to 320° F., and will all distil off below a temperature 45 of about 600° F.

The term "end boiling point" in the specification and claims is used to designate the highest boiling point of any of the constituents of commercial naphtha or illuminating 50 oil. Since in nature there is no line of division between these substances, and since the commercial line of division has changed and is subject to change in the future, no more definite term can be used and no more

definite figures can be given. For example, 55 it is a matter of common knowledge that as the demand for naphtha or gasoline has increased much more rapidly than the demand for illuminating oil and as improvements have adapted gas engines to utilize heavier 60 grades of gasoline, the end boiling point of commercial gasoline has progressively risen, and the initial boiling point of commercial illuminating oil has correspondingly risen.

Whatever may be the end-boiling-point of 65 commercial naphtha or of illuminating oil, the principle remains the same—that is to say, if the temperature of the vapor given off is maintained not above 325° F., substantially the whole body of the higher-boiling 70 point hydrocarbons may be, if desired, converted into hydrocarbons having boiling points not above that temperature; and if the temperature is maintained not above 350° F., substantially the whole body may 75 be, if desired, converted into hydrocarbons having boiling-points not above that temperature. The same principle exactly would apply if, in the future, commercial naphtha should include constituents having boiling- 80 points as high as 400° F., or higher.

As an example, I may take 100 parts of petroleum distillate freed from naphtha products—such as gas oil made from a paraffin or semi-paraffin or semi-asphalt 85 crude oil—and add to it 5 parts of a suitable agent—such as anhydrous aluminum chlorid, for example. The mixture is then heated to a temperature at which the vapor given off is not substantially above 325 degrees to 90 350 degrees F. The still is preferably provided with stirring apparatus of any known and approved form to keep the aluminum chlorid in suspension and in intimate contact with the oil, and to prevent over-heating it. Preferably also fresh charges of oil are added from time to time as the charge becomes low, to avoid distilling the contents to dryness, and to obtain the advantage of the repeated use of the reducing agent, the 100 efficiency of which appears to persist for a considerable time. If the charge were distilled to dryness, the agent would be lost, coke would be formed and the cleaning of the still after each charge would be required. 105 If desirable, additional aluminum chlorid may be added from time to time, as required. The use of a larger percentage of anhydrous

aluminum chlorid than that named in the above example—say 10 parts to 100 parts of oil, for example—causes the desired reactions to take place much more rapidly. The 5 result of the process is to break up the complex molecules of the oil into the simpler molecules of naphtha or gasoline, which passes to a suitable condensing apparatus, and is there collected. In this way I have 10 converted the entire body of the oil into naphtha or gasoline and gases and have recovered from 70 to 80 per cent. in the form of naphtha or gasoline, the remainder being converted into gases which escaped, or was 15 left in the still in the form of coke and organic matters.

While I am not able at the present time to give an account of the reactions which take place, present information suggests that the 20 action of the agent is wholly or partially catalytic. There is, however, some loss of the agent by combination or reaction with impurities in the oil—such, for example, as by reaction with the sulfur present, which is 25 indicated by the strong odor of hydrogen sulfid—and perhaps by combination with the oil itself. Other equivalent agents may be used in combination with, or in place of, anhydrous aluminum chlorid—such, for example, as anhydrous ferric chlorid, and, perhaps, other substances which, up to the present, I have not had time to try. The use of equivalent agents is included within the scope of my claims. I have found anhydrous ferric chlorid to be a less active agent than anhydrous aluminum chlorid and that it is necessary to use larger quantities of it to effect the same result.

When the temperature of the vapor is not 40 raised above about 325 degrees to 350 degrees F., or even somewhat higher, the naphtha produced can be sold directly in commerce at the present time as automobile or stove gasoline, and the end-boiling-point 45 of such gasoline is continually rising; or it may be redistilled and separated into gasolines of different gravities in the usual manner. It is superior to the naphtha or gasoline produced by direct distillation 50 from crude oil in that it is substantially free from unsaturated hydrocarbons, as is shown by the well-known sulfuric acid test. The process above described may also be practised with illuminating oil or lubricating oil 55 as starting materials. It may also be practised with crude oil as the starting material, but it is less advantageous to use crude oil because of its contained impurities.

Instead of maintaining the still at the low 60 temperatures above described, I may increase the temperature up to about 550 degrees to 600 degrees F., in which case the distillate consists of naphtha and illuminating oil, which may be separated by fractional distillation in the usual way. Not

much illuminating oil is produced between the temperatures of 400 degrees to 450 degrees F. As the temperature increases above that, the percentage of illuminating oil increases, since in general it may be said that the lower the temperature is maintained, the lighter the gravity of the distillate will be. If temperatures substantially higher than 600 degrees F. were employed, not only would oils be carried over into the condenser of higher boiling points than illuminating oil, but the reducing agent would be driven off, resulting not only in loss of that agent, but also in clogging the pipes.

In the drawing I have shown one form of still which is suitable for use in the practice of my process, although it will be understood that any other form of still which is suitable may be used.

In the drawing A is the still. 85 B is a shaft rotated by a pulley C and gears D. The shaft B carries stirring blades E, E', the lower blades E' carrying depending chains F.

G are splash plates attached to the shell of 90 the still.

H is a manhole, and I a discharge opening at the bottom.

J is the vapor exhaust pipe, and K is an inlet pipe for oil and chemicals.

What I claim and desire to secure by Letters Patent of the United States is:—

1. The process of converting hydrocarbons having higher-boiling-points into naphtha, which consists in heating said hydrocarbons in the presence of anhydrous aluminum chlorid to a temperature producing vapor having a temperature not substantially above the end-boiling-point of naphtha and maintaining them at such temperature.

2. The process of converting hydrocarbons having higher-boiling-points into hydrocarbons having lower-boiling-points, which consists in heating said hydrocarbons in the presence of anhydrous aluminum chlorid, to a temperature producing vapor having a temperature not substantially above the end-boiling-point of illuminating oil and maintaining them at such temperature.

3. The process of converting hydrocarbons having higher-boiling-points into naphtha, which consists in heating said hydrocarbons in the presence of anhydrous aluminum chlorid, to a temperature producing vapor having a temperature not substantially above the end-boiling-point of naphtha and maintaining such vapor temperature until the greater part of the oil has been separated as naphtha.

4. The process of converting hydrocarbons having higher-boiling-points into hydrocarbons having lower-boiling-points, which consists in heating said hydrocarbons

in the presence of anhydrous aluminum chlorid, to a temperature producing vapor having a temperature not substantially above the end-boiling-point of illuminating oil and maintaining such vapor temperature until the greater part of the oil has been separated as naphtha and illuminating oil.

In testimony whereof I have hereunto signed my name in the presence of two subscribing witnesses.

GEORGE WILLIAM GRAY.
